REFRIGERATOR CABINET OR SIMILAR ARTICLE

Lawrence R. Collins and Robert E. Munz, Jefferson County, Ky., assignors to General Electric Company, a corporation of New York

Filed Mar. 25, 1960, Ser. No. 59,877

Term of patent 3½ years

(Cl. D67—3)

FIG. 1

FIG. 2

FIG. 3

FIGURE 1 is a front perspective view of a refrigerator cabinet or similar article embodying our new design;

FIGURE 2 is a cross section on the line 2—2 of FIGURE 1 in the direction of the arrows; and

FIGURE 3 is a cross section on the line 3—3 of FIGURE 1 in the direction of the arrows.

The dominant features of our design reside in the portions shown in full lines.

We claim:

The ornamental design for a refrigerator cabinet or similar article, substantially as shown and described.
